UNITED STATES PATENT OFFICE.

LARS S. LARSEN, OF ST. PAUL, MINNESOTA.

GLARE-PREVENTING ATTACHMENT FOR AUTOMOBILE HEADLIGHTS.

Application filed September 19, 1923.; Serial No. 663,642.

To all whom it may concern:

Be it known that I, LARS S. LARSEN, a citizen of the United States, residing at St. Paul, in the county of Ramsey and State of Minnesota, have invented certain new and useful Improvements in Glare-Preventing Attachments for Automobile Headlights, of which the following is a specification, reference being had therein to the accompanying drawings.

This invention relates to a glare preventing attachment for automobile headlights and it has for its object to provide adjustable reflecting elements mounted directly upon the casing of the headlights in such manner that the light rays may be confined to just the desired extent and in such manner that the driver of an oncoming vehicle will not be blinded or dazzled by such light rays. It is a well known fact that a large proportion of the serious automobile accidents are caused by the dazzling or blinding of the driver of the vehicle by the headlights of another machine. It is therefore a primary object of the present invention to provide means for preventing these accidents, said means being of such a nature that they will not be subject to excessive rattling and will not be likely to get out of order.

A further object of the invention is the provision of a novel ray deflector adapted to be mounted in the usual reflector of the headlight and acting to direct the rays upon the adjustable reflecting elements in such manner that the latter may thereafter reflect them downwardly upon the roadbed as hereinafter described.

Further objects and advantages of the invention will be set forth in the detailed description which follows.

In the accompanying drawings:

Fig. 1 is a side elevation of a headlight provided with my improvement;

Fig. 2 is a plan view thereof;

Fig. 3 is a front elevation upon a reduced scale;

Fig. 4 is a vertical section through a lamp provided with my improved ray deflector in conjunction with the adjustable reflectors;

Fig. 5 is a horizontal section on line 5—5 of Fig. 4; and

Fig. 6 is a perspective view of the ray deflector.

Like numerals designate corresponding parts in all of the figures of the drawings.

In the drawings 5 designates the casing of a conventional headlight of the parabolic type. In carrying out the invention I provide a plurality of reflecting shields. 60 In the particular embodiment of the invention shown in Figs. 1 to 3 of the drawings, I have illustrated a top shield 6 and a pair of side shields 7 and 8. These shields are hinged to the casing 5 at 9, 10 and 11. The shields may be made of metal and nickel plated to render them highly reflecting or they may be of mirror-like material. The particular construction of these shields is immaterial, it only being necessary, in order to secure the desired results, to provide shields which will catch the rays which would ordinarily be directed upwardly and laterally and divergent from the axis of the headlights and direct them straight ahead 70 and below the line of vision of the driver of an oncoming automobile. Many ways may be provided for holding these shields in adjusted position. However, it is essential that the means provided be such as to 80 rigidly support the shields against excessive rattling and with this end in view I have provided rods 12 which are hinged at their rear ends between ears 13 of the lamp casing and the forward portions of which 85 slide through trunnion blocks 14 which are pivoted between ears 15 of the several shields. Screws 16 bind these rods in adjusted position and consequently hold the shields in the particular position to which 90 they may be adjusted.

I further contemplate using a deflector such as is illustrated in Figs. 4, 5 and 6 of the drawings in conjunction with the reflectors, though it is to be understood that the 95 reflectors may be used without the deflector and advantageous results secured. This deflector comprises a web 20 carrying a substantially conical member 21 at its central portion and an inclined curved web 22 at 100 its top side. The rear portion of the web 20 is cut out, as indicated at 23, for the reception of the usual light bulb 24 carried by the usual reflecting surface 25. The lower portion of the cone 21 prevents rays 105 from passing straight ahead but permits the passage ahead only of those rays which are directed downwardly. The upper portion of the cone 21 prevents the passage of rays straight ahead from the bulb 24 and in conjunction with the inclined web 22 permits the passage only of those rays which are 110

- inclined upwardly or outwardly to such an extent as to impinge upon the reflectors shields 6^a, and 7^a, at such an angle that the shields will, in turn, act to direct these rays 5 downwardly at such an angle that they will strike the roadbed a comparatively short distance ahead of the vehicle and thus be prevented from dazzling an oncoming driver.
- 10 Thus it will be seen that I have provided an attachment for automobile headlights comprising a plurality of independently adjustable screens and reflectors which serve to confine the light rays and to direct these 15 light rays ahead at just the angle desired.

Thus all of the light is conserved and directed upon the road at the place where it will serve the most useful purpose in illuminating the roadway for the driver, while at 20 the same time drivers of approaching vehicles are not subjected to annoyance and dangerous glare.

It is to be understood that the invention is not limited to the precise construction set 25 forth but that it includes within its purview whatever changes fairly come within either the terms or the spirit of the appended claims.

Having described my invention what I 30 claim is:

1. The combination with a headlight of a plurality of reflectors hinged at their rear ends to the casing of the headlight wholly outside of the diameter of the headlight and 35 projecting forwardly beyond the front edge of said headlight, rods hinged to the casing of the lamp, pivoted trunnion blocks upon the reflectors through which said rods slide and means for binding said rods into engagement with said trunnion blocks.

2. The combination with a lamp comprising

ing a reflector and a source of light, a plurality of reflecting shields projecting forwardly therefrom outside of the diameter of the lamp and a ray deflector adjacent the 45 source of light to intercept those rays which would normally pass substantially straight forward from the source of light and directing those rays outwardly upon said shield.

3. The combination with a lamp, its reflector and light bulb, of a ray deflector comprising a transverse horizontal web, a substantially conical member centrally disposed with respect to said web and a curved inclined web carried by the first named web 55 and of much greater arc than said conical member in combination with reflecting shields upon which the light passing forwardly from said deflector impinges.

4. The combination with a lamp, its reflector and light bulb, of a ray deflector comprising a transverse horizontal web, a hollow conical member open at both ends and centrally disposed both laterally and vertically with respect to said web and having 65 its largest end disposed outwardly and a curved inclined web carried by the first named web lying wholly thereabove of much greater arc than said conical member and having its part of greatest diameter disposed 70 outwardly, the first named web being cut away at its rear side for the reception of a light bulb.

5. A structure as recited in claim 4 in combination with reflecting shields disposed 75 wholly outside of the diameter of the lamp by which the reflector is carried, said reflectors serving to direct light rays from the light bulb upon said shields.

In testimony whereof I hereunto affix my 80 signature.

LARS S. LARSEN.
